Des. 214,632
Patented July 8, 1969

214,632

WORK DESK FOR A BEAUTICIAN

Bernard Leprince, 5921 Onondada Road,
Bethesda, Md. 20016

Filed Feb. 7, 1968, Ser. No. 10,475

Term of patent 14 years

Int. Cl. D6—01

U.S. Cl. D33—7

FIG. 3

FIG. 2

FIG. 4

FIG. 5

FIG. 1 is a front perspective view of a work desk for a beautician showing my design;

FIG. 2 is a front elevation;

FIG. 3 is a top plan;

FIG. 4 is a bottom plan; and

FIG. 5 is a side elevation.

The side of the article not shown is plain while the back is conventionally flat.

I claim:

The ornamental design for a work desk for a beautician, as shown and described.
